UNITED STATES PATENT OFFICE.

ANDREW G. PAUL, OF BOSTON, MASSACHUSETTS.

HEATING SYSTEM.

No. 899,839.

Specification of Letters Patent. Patented Sept. 29, 1908.

Application filed May 15, 1900. Serial No. 16,815.

To all whom it may concern:

Be it known that I, ANDREW G. PAUL, a citizen of the United States, residing in Boston, in the county of Suffolk and State of Massachusetts, have invented a new and useful Improvement in Heating Systems, of which the following is a full, clear, and exact specification, reference being had to the accompanying drawings, which form a part hereof.

This invention relates to a heating system wherein steam or other suitable heating agent is circulated for the purpose of conveying and imparting heat to the places desired, and it consists in an improved construction and arrangement of the parts of such a system.

One object of my invention is to control the heating of the room or apartment and at the same time the ventilation thereof, by means of the pressure within the system or heater.

Another object of my invention is to control both the amount of heating vehicle which is supplied to the system, and the amount of air which is supplied through an air duct to the room or apartment being heated by the pressure within the system or heater.

My invention is fully shown in the accompanying drawings, in which

Figure 1 shows my invention embodied in a system in which the supply valve, and an air duct opening at the rear of the radiator, are controlled by the pressure within the radiator. Fig. 2 is a side view, partly in section, of the system shown in Fig. 1. Fig. 3 shows my improved system applied to what is ordinarily termed an indirect heating stack. Fig. 4 is a sectional view of the diaphragm and connected parts. Fig. 5 is a sectional view of the valve 42.

Similar numbers denote similar parts in the different figures.

Referring to Figs. 1 and 2, 1 is a radiator or heater of any suitable construction; 2 is a supply pipe; 3 is a supply valve; 4 is a discharge pipe; 5 is a check valve on the discharge pipe; 6 is a tank for the water of condensation; 7 is a relief pipe from said tank provided with a check valve 8 or any other suitable form of valve.

9 is a cock for drawing off the water of condensation.

10 is a pipe through which the water of

condensation can be pumped to the boiler or to any other place desired.

11 is an air duct opening behind the radiator as shown, and provided with the valve or damper 12.

13 is a diaphragm suitably held or supported in a casing 14.

15 is a fluid pressure chamber underneath the diaphragm connected by means of the pipe 16 with the radiator.

17 is a solenoid valve on the pipe 16 controlled in any suitable manner by the thermostat 18, which is adapted to be placed upon the wall of the room or apartment to be heated or in any other suitable position. As shown, the thermostat 18 is connected with the valve 17 by means of the electric circuit 19, including a battery or generator 20. The fluid pressure chamber 15 is provided with any suitable form of vent such as an ordinary pin-hole opening.

21 is an arm fastened in any suitable way to the diaphragm, and pivoted to the lever 22, which is fulcrumed at 23. One arm of the lever 22 is connected by means of the rod 24 with the supply valve 3. The other end of the lever is connected with the damper 12 by means of the rod 25, the bell-crank lever 26, and the link 27.

28 is an air pipe provided with an exhauster 29 and with an ordinary automatic air valve 30.

31 is an air pipe running from the exhauster to the tank 6, provided with an automatic air valve 32 as shown.

33 is a screw supported in a post rising from the casing 14 of the diaphragm, and at its lower end carrying a loop 34, encircling the lever 22 as shown. By this means the lever 22 can be moved in either direction so as to open or close the supply valve and the valve 12, or limit the extent of their opening.

The operation of this apparatus is as follows. Assuming that the valve 17 is open, the system is started either by opening the supply valve and the air duct by means of the screw 33 or by putting the exhauster 29 into operation. The air is drawn out from the radiator through the air pipe 28. The heating vehicle enters the radiator and fills the same. At the same time the air valve or damper 12 is opened and a current of air is introduced into the room and passes in contact with the radiator so as to be heated.

thereby. As soon as the pressure in the radiator rises above the desired or predetermined point, this pressure operates upon the diaphragm 13 and causes it to move the lever 22 and thereby to close the supply valve 3 and the valve 12 in the air duct, thus cutting off the supply of heating vehicle to the radiator, and at the same time cutting off the current of air through the duct 11. When the pressure falls below the desired or predetermined point, the diaphragm 13 is moved in the opposite direction, thereby again opening the supply valve and the air duct. A fresh quantity of heating vehicle is introduced into the radiator, and at the same time a current of air is heated and allowed to escape into the room. This operation continues until the room is sufficiently heated. The thermostat 18 being then expanded, closes the circuit 19 and thereby closes the valve 17 in the pipe 16, thus shutting the radiator off from the fluid pressure chamber 15. The pressures of the two sides of the diaphragm 13 are then equalized through the vent, as a result of which the supply valve and the valve or damper 12 are both closed and are kept closed so long as the temperature in the room remains at or above the desired point. Should the temperature of the room fall below this point, the valve 17 is again opened and the radiator is brought into operation as already explained. The water of condensation passes out through the discharge pipe 4 into the tank 6. The air is removed from the radiator through the air pipe 28 by the exhauster 29.

It will be seen that the room is heated not only by the direct radiation of heat from the radiator, but also by the current of air passing into the room from the duct 11 which is heated as it passes by the radiator, and that in this way the room is ventilated as well as heated.

In Fig. 3 the parts are the same as already described with the following differences. 35 is a heating stack placed in an air flue 36 which opens into the room or other place to be heated. The lever 22 is connected at one end with the supply valve as already explained, and at the other end by means of the rod 37 and link 38 with the valve or damper 39, which is placed in the air duct preferably between the stack 35 and the outer end of the air duct. The pipe 16 connecting the fluid pressure chamber of the diaphragm with the stack is provided with an ordinary hand valve 40 in addition to the solenoid valve 17. The supply pipe is also provided with an ordinary shut off valve 41. The discharge pipe from the stack is provided with a discharge valve 42. The construction of this valve 42 is shown in Fig. 5 in which 50 is the valve casing, 51 is a discharge port at its lower end, 52 is a piston provided at its lower end with a valve 53

adapted to close the port 51, 54 is a passage for air or gas or vapor between the piston and the wall of the casing, 55 is a fluid pressure chamber above the piston, 56 is a passage in the casing connecting the fluid pressure chamber with the discharge pipe beyond the discharge port 51, 57 is a spring one end of which bears against the upper side of the piston and the other end of which bears against the lower surface of a screw 58 by means of which the tension of the spring can be adjusted, and 59 is a cap to protect the screw 58.

43 is an ordinary hand valve on the discharge pipe, 44 is an exhauster connected with the discharge pipe, and 45 is a valve for cutting out the exhauster. The operation of this form of apparatus is substantially the same as that already explained. The system is started by putting the exhauster 44 into operation, thereby drawing out the air from the stack 35 and reducing the pressure therein which causes the diaphragm 13 to open the supply valve 3 and at the same time the valve 39 in the air duct. When the pressure in the stack rises above the desired or predetermined point, it operates upon the diaphragm 13 and shuts both the supply valve and the air duct valve. When the pressure in the stack falls below this desired or predetermined point, these valves are again opened. The water of condensation and the air are removed from the system through the discharge valve by the operation of the exhauster 44. When the thermostat 18 is employed, the pipe 16 is closed as soon as the room reaches the desired temperature as already explained.

Some of the advantages of my invention are as follows. The system can be run at any predetermined pressure in the heater or radiator according to the work which is to be performed. This pressure is regulated and controlled accurately and automatically. When the system is put into operation a current of fresh air is supplied to the room, thereby accomplishing two purposes, first, ventilating the room and also serving to heat the room as this air is heated by the radiator in passing by the radiator. This produces a circulation of air in the room, and thereby aids in the ventilation of the room. At the same time the air and water of condensation are automatically and efficiently removed from the system. By employing the thermostat in the room or place to be heated, the heating system can be turned on or off according to the conditions prevailing in this room, and the amount of heat supplied thereto can thus be properly and economically controlled.

What I claim as new and desire to secure by Letters Patent, is:

1. The combination with a heating system, of a supply pipe, a supply valve and an

air duct, a valve in the air duct, a motor controlling both of said valves and connected with the heater or radiator so as to be operated by the pressure within, substantially 5 as set forth.

2. The combination with a heating system, of a supply pipe, a supply valve, an air duct, a valve in the air duct, a motor controlling both of said valves, a casing provided with a fluid pressure chamber on one 10 side of said motor, and a pipe connecting the fluid pressure chamber with the heater or radiator, substantially as set forth.

3. The combination with a heating system, of a supply pipe, a supply valve, an air duct, a valve in the air duct, a motor controlling both of said valves and connected with the heater or radiator so as to be operated by the pressure therein, a discharge pipe, a discharge valve, a casing, a 15 motor controlling said discharge valve, the casing being provided with a fluid pressure chamber on one side of said motor, and with a passage connecting the fluid pressure chamber with the chamber on the other side of said motor, a pipe connecting said fluid pressure chamber with the discharge pipe, and an exhauster connected with the exhaust pipe, substantially as set forth.

4. The combination of a heating system, a supply pipe, a supply valve, an air duct, a valve in the air duct, a motor controlling both of said valves, a casing provided with a fluid pressure chamber on one side of said 20 motor and a pipe connecting the fluid pressure chamber with the heater or radiator, a discharge pipe, a discharge valve, a piston controlling said discharge valve, a casing provided with a fluid pressure chamber on 25 one side of said piston, and with an air passage connecting the fluid pressure chamber with the chamber on the other side of said piston, a pipe connecting said fluid pressure chamber with the discharge pipe, and an exhauster connected with the discharge pipe, substantially as set forth.

sage connecting the fluid pressure chamber with the chamber on the other side of said piston, a pipe connecting said fluid pressure chamber with the discharge pipe, and an exhauster connected with the discharge 45 pipe, substantially as set forth.

5. The combination with a heating system of a supply pipe, a supply valve, an air duct, a valve in the air duct, a motor controlling both of said valves, a casing 50 provided with a fluid pressure chamber on one side of said motor, and a pipe connecting the fluid pressure chamber with the heater or radiator, and a thermostat controlling said passage, substantially as set forth.

6. The combination of a heating system, a supply pipe, a supply valve, an air duct, a valve in the air duct, a motor controlling both of said valves, a casing provided with a fluid pressure chamber on one side of said 55 motor, a pipe connecting the fluid pressure chamber with the heater or radiator, and a thermostat controlling said pipe, a discharge pipe, a discharge valve, a motor controlling said discharge valve, a second casing provided with a fluid pressure chamber on one side of said motor, and with an air passage connecting the fluid pressure chamber 60 with the chamber on the other side of said motor, a pipe connecting said fluid pressure chamber with the discharge pipe, and an exhauster connected with the discharge pipe, substantially as set forth.

In testimony whereof, I have signed my name to this specification, in the presence of 75 two subscribing witnesses.
